(57) **CLAIM**

The ornamental design for a display screen or portion thereof with computer-generated icon, as shown and described.

DESCRIPTION

FIG. 1 is a front view of a first embodiment of a computer-generated icon for a display screen or portion thereof illustrating my new design;

FIG. 2 is a front view of a second embodiment thereof;

FIG. 3 is a front view of a third embodiment thereof;

FIG. 4 is a front view of a fourth embodiment thereof;

FIG. 5 is a front view of a fifth embodiment thereof;

FIG. 6 is a front view of a sixth embodiment thereof;

FIG. 7 is a front view of a seventh embodiment thereof;

FIG. 8 is a front view of an eighth embodiment thereof;

FIG. 9 is a front view of a ninth embodiment thereof;

FIG. 10 is a front view of a tenth embodiment thereof;

FIG. 11 is a front view of an eleventh embodiment thereof;

FIG. 12 is a front view of a twelfth embodiment thereof;

FIG. 13 is a front view of a thirteenth embodiment thereof;

FIG. 14 is a front view of a fourteenth embodiment thereof;

FIG. 15 is a front view of a fifteenth embodiment thereof;

FIG. 16 is a front view of a sixteenth embodiment thereof;

FIG. 17 is a front view of a seventeenth embodiment thereof;

and,

FIG. 18 is a front view of an eighteenth embodiment thereof.

In all views, the dotted lines of the display screen or portion thereof and of the electronic device are for illustrative

purposes only and form no part of the claimed design.
